UNITED STATES PATENT OFFICE

EDWIN H. STELZER, OF ST. LOUIS, MISSOURI, ASSIGNOR OF ONE-HALF TO MILTON F. NAPIER, OF ST. LOUIS, MISSOURI

TRENCH COVER

Application filed November 25, 1927. Serial No. 235,433.

This invention relates to trench covers, and has for its principal object the provision of a permanent device that may be employed as a temporary pavement or safety closure when placed over plumbers' cuts, sewer trenches, 5 new openings in streets to receive conduits or gas or water mains, or over excavations of like character, or pavements in course of construction. Traffic can move without interruption or danger over cuts, trenches, and new 10 openings that have been closed by the cover of this invention; and the use of barricades and red lights in connection therewith is obviated.

Other objects and advantages, more or less 15 ancillary to the foregoing, will appear in the course of the following description of preferred embodiments of the invention.

In the accompanying drawings forming 20 part of this specification, in which like numbers of reference denote like parts wherever they occur,

Figure 1 is a bottom plan view of one form 25 of the cover, showing the normally depending legs, hereinafter referred to, in collapsed position;

Figure 2 is a vertical longitudinal sectional view taken on the line 2—2 in Figure 1, but with the legs depending;

Figure 3 is a transverse vertical sectional 30 view taken on the line 3—3 in Figure 2;

Figure 4 is a horizontal fragmentary sectional view taken on the line 4—4 in Figure 2;

Figure 5 is a transverse vertical sectional 35 view taken on the line 5—5 in Figure 2;

Figure 6 is a bottom view of another form 40 of the invention, showing the depending legs in retracted position;

Figure 7 is a top view of the same;

Figure 8 is a vertical longitudinal central 45 sectional view of the same as it appears with the legs extended;

Figure 9 is an end view of the cover as shown in Figure 6;

Figure 10 is a vertical sectional view taken 50 on the line 10—10 in Figure 6; and

Figure 11 is a vertical sectional view taken 55 on the line 11—11 in Figure 6.

The cover may be formed of any suitable

materials that have been given the desired configuration in any suitable manner; but for the purpose of illustrating the invention, and not in a limiting sense, I have herein shown one form of a cover that is fabricated of sheet or plate steel, and another form that is formed of cast steel. In the plate-steel form of the invention, exhibited in Figures 1 to 5, inclusive, the device comprises a floor plate 1 that rises gradually from the edges toward the central portion so as to present a concave bottom and a convex top, the extreme marginal portions 2 preferably being flat and the central portion 3 of the plate 1 being nearly flat, so that the rise is effected along an ogee curve, the curvature adding stiffness to the plate. A wrought iron frame 4 is welded against the underside of the flat marginal portions 3 so as to form a depending marginal flange thereunder that adds rigidity to the plate 1. Three pairs of channel beams 5 and 6, 7 and 8, and 9 and 10, respectively, are welded to the bottom of the plate 1 and extend laterally thereof, the pair of channels 5 and 6 being disposed at the middle of the plate 1 and the other pairs each about two-thirds of the way from the middle in opposite directions. The channels of each pair are spaced apart to accommodate therebetween the hinges of the pivoted side walls or doors that will presently be described. A pair of channel beams 11 and 12 extend longitudinally along the underside of the plate 1, the said channels being preferably spaced as far from one another as they are from the longer sides of the plate 1. The said channels 11 and 12 have their continuity interrupted by the intersection therewith of the laterally extending channels 5, 6, 7, 8, 9, and 10, and are, therefore, formed in sections that are recessed to accommodate the said laterally extending channels and are preferably welded thereto and to the bottom of the plate 1. Channels 11 and 12 do not extend across from channel 7 to channel 8, and from channel 9 to channel 10, in order to allow room for the vertically extending channel-shaped brackets 13, whose flanges are riveted or otherwise suitably secured to the channels 7, 8, 9, and 10. The brackets 13 are arranged in pairs 55 60 65 70 75 80 85 90 95 100

of oppositely disposed members, suitably spaced apart to accommodate therebetween the hinges 14 of the end walls or doors 15, the said hinges being disposed at opposite ends of the said doors and pivoting on cotter pins 16, that pass through holes therefor in the webs of the brackets 13. Cotter pins 17 pass through holes therefor in the webs of the channels 5, 6, 7, 8, 9, and 10, and are axially aligned in two rows that extend longitudinally of the plate 1 in proximity to the outer ends of the hinges 14 of the end walls 15. The hinges 18 of side walls or doors 19 pass around and pivot on the cotter pins 17. The lower faces 20 of those portions of the channel bars that overlie the doors when the latter are folded thereagainst are disposed higher than the plane of the lower or bearing face 21 of the flange 4, so that the doors or legs, when collapsed against the plate 1, will not project below the plane of the face 21.

The doors or legs 15 and 19 normally depend by gravity from the bottom of the plate 1 so as to form the vertical walls of a rectangular enclosure. Angle plates 22 connect or lock the end walls or legs 15 to their adjacent side legs or walls 19 and are slidably borne by the walls 15 through the intermediary of a T-shaped tongue 23, whose neck 24 passes through a slot 25 in that flange 26 of plate 22 that rides on the wall 15, and is suitably secured at its inner edge to the wall 15. The flange 27 of plate 22 that rides on wall 19 is perforated by a slot 28, that extends nearly from the lower to the upper edge of the flange 27 and is inclined so that its upper end is disposed closer to the flange 26 than its lower end. A stud 29 passes through the slot 28, and is suitably secured at its inner end to the side plate 19. The head 30 of stud 29 will pass through the enlarged lower end 31 of slot 28, but not through the other portions thereof. To lock the end plates 15 to the side plates 19, the angle plates 22 are lifted so that the heads 30 of the studs 29 will pass through the slot enlargements 31, and are then lowered, the shanks or necks of studs 29 entering the upper obliquely disposed constricted portion of the slots 28, whereby the end plates 15 are drawn or wedged tightly against the adjacent ends of the side plates 19, thereby forming a rigid box-like structure. The end plates or members 15 are extended longer than the side members 19 at their middle portions, the extended portions having obliquely disposed sides 32 connected by an arcuate end 33, thereby forming a skid to enable the cover to be easily set over a trench or excavation. The plates 15 and 19 preferably are provided with perforations 34 to receive nails or other attaching devices whereby additional means, such as suitable lumber or the like, for bracing the sides and ends of a trench may be secured thereto.

A device is provided on the bottom of the

plate 1 to hold the pivoted members 15 and 19 in the folded compact position shown in Figure 1, so that transportation and handling of the cover from one job to another is facilitated. This device consists of a plate 35 bent to channel or U-shape to provide a pair of parallel flanges 36 connected by an intervening web 37 at one end and having outwardly extending lateral flanges 38 at their other ends. Web 37 is pivotally connected at 39 to the center of the underside of the plate 1. Notches 40 are formed in the inner edges of the legs 19 so that the legs 19 will clear the plate 35 when the latter is turned at right angles to the position in which it is shown in Figure 1. With plate 35 turned at right angles to the position shown in Figure 1, the doors 15 can be folded against the plate 1, and door 19 then folded against the doors 15 as shown in Figure 1, and the doors may then be locked in this collapsed position by turning plate 35 to the position shown in Figure 1, for, with the lock 35 so positioned, the flanges 38 of lock 35 intercept the edges 41 of the notches 40 and thereby prevent the opening of the doors 19, whereby the opening of the doors 15 is in turn prevented. The edge portions 41 are bowed to pass behind the flanges 38; and the lower flanges 42 of the channel bars 5 and 6 are bowed at 43 to accommodate the bowed edge portions 41 of the doors 19, so that neither the doors 9 and 15, nor the device 35 projects below the plane of the bottom face of the marginal base flange 4. When the cover is in the collapsed position shown in Figure 1, it can be placed over a newly made concrete pavement as a protection to the pavement while the concrete is setting. The cover is preferably held in place over the concrete by means of two rods, set into the concrete base and bolted to the cover. Portions of the upper face of the cover are depressed or countersunk to accommodate nuts for the threaded upper ends of the said rods. In the plate steel embodiment of the invention, the depressed face or bearing for the nuts is provided by forming holes 44 in the plate 1 through which the nuts can be passed, and securing a bracket 45 to the underside of the plate 1 under each of the holes 44. The nuts react against the webs 46 of the brackets 45; and the threaded ends of the rods pass through holes 47 in the webs 46. After the cover is removed from the finished repair, the rods or anchor bolts can be cut off flush with the pavement.

A series of holes 48 are provided in the marginal portions 2 of the plate 1 to receive suitable attaching devices, such as spikes to fasten the cover to the pavement after the repair is made and the cement base is setting, or bolts to secure a plurality of such covers together in series, as may be necessary to cover a long trench.

It will be observed that the doors 9 and 15

15, when they are locked in their depending position, as shown in Figures 2, 3, and 5, co-operate with the sides of a trench to prevent lateral shifting of the cover under constant impact of heavy trucks and busses, and they, also, serve to line and reinforce the walls of a trench or excavation and thereby prevent the top edges or other fragile portions of the said walls from caving in. The 5 gradual rise of the top of the cover from its edges, moreover, insures that vehicles passing thereover will not be unduly jarred or swerved from their courses. The top face of the plate 1 is preferably rough or covered 10 with anti-skid conformations to prevent skidding of vehicles passing thereover. If the cover be fabricated of plate steel, as shown in Figures 1 to 5, inclusive, the plate 1, for this reason, is preferably formed of rolled 15 steel plate of the "safety tread" type.

In the cast steel cover illustrated in Figures 6 to 11, inclusive, the marginal base flange 49 and the reinforcing webs or ribs 50 are cast integral with the top plate 51. The 20 marginal holes 52 pass through recessed or countersunk portions 53 of the plate 51, thereby affording an even bearing for the heads or nuts of bolts that pass through the holes 52. The upper corners of the end legs 54 and 25 side legs 55 present lugs or ears 56 that are pivoted to lugs or ears 57 cast integral with the plate 51. The middle portions of the 30 upper edges of legs 54 and 55 present ears 58, having therethrough openings 59 that register with openings 60 in ears 61, cast integral with plate 51, when the legs are extended in their depending positions, as shown in full lines in Figure 8 and in dotted lines in Figure 10. Pins 62, when inserted through adjacent 35 aligned openings 59 and 60, secure the legs 54 and 55 in their depending positions. When the pins 62 are removed from the openings 59 and 60, the legs may be folded against the plate 51, as shown in Figures 6, 10, and 11, 40 and secured in this retracted position by means of the plate 63, pivoted to stud 64, held in a boss 65, cast integral with plate 51. When plate 63 is turned to the position shown in Figure 6, its ends underlie the adjacent portions 45 of the side legs 55, thereby sustaining the legs 55 in a horizontal position; and protuberances or lugs 66, cast integral with the end legs 54, project therefrom so as to overlie legs 55, thereby retaining the legs 54 in their horizontal position. Manifestly, if plate 63 50 is turned to a position at right angles to the position shown in Figure 6, it will be disengaged from the legs 55, thereby allowing legs 55, and consequently legs 54, to drop to their 55 depending positions. Plate 51 courses or bulges upwardly at 67 over the ears 58 and 61 to provide clearance for the ears 58 without unduly raising the level of the top face of the plate 51. Openings 68 are cast in plate 65 51 to lighten the plate and, also, to provide

anti-skid conformations on its upper face. Bulges 67, also, form anti-skid conformations. Plate 51 presents a pair of depressed portions 69 to provide a countersunk face for nuts for threaded rods that may be passed through the openings 70 in the depressed portions 69 and imbedded in a newly made concrete pavement thereunder to hold the cover in position thereover until the pavement has set. 70

Having thus fully described this invention, I hereby reserve the benefit of all changes in form, arrangement, order, or use of parts, as it is evident that many minor changes may be made therein without departing from the spirit of this invention or the scope of the 75 following claims.

I claim:

1. A cover of the character described having a plurality of hinged members adapted to depend therefrom to cooperate with adjacent walls to keep the cover within proper bounds. 80
2. A cover of the character described embodying walls adapted to be collapsed against the cover and to be extended to line the sides of an excavation. 90
3. A cover of the character described having a plurality of members pivoted thereto so that they may be folded toward the underside of the cover and toward the walls of a trench covered thereby so as to cooperate with the walls to keep the cover within lateral limits. 95
4. A cover of the character described having a plurality of plates pivoted thereto so that they may be folded toward the underside of the cover and toward the sides of a trench covered thereby. 100
5. A cover of the character described embodying means adapted optionally to be collapsed against the cover and to be extended along the sides of an excavation and means for locking the said means from being shifted from a selected position. 105
6. A cover of the character described embodying oppositely disposed walls pivotally depending therefrom so that they may be swung toward one another, and means pivoted to the cover intermediary of said walls and adapted when in one position to clear said walls when they are swung toward and from their depending position, and in another position to obstruct the said swinging movement, thereby to lock the walls from returning to their depending position. 110
7. A cover of the character described embodying a plurality of walls pivoted thereto so that they may be swung toward the cover and extended therefrom to form corners between adjacent walls, and means for locking adjacent walls together. 115
8. A cover of the character described embodying a plurality of walls pivoted thereto so that they may be swung toward the cover and extended therefrom to form cor- 120
- 130

- 5   ners between adjacent walls, a slotted plate
    slidably borne by one of said walls, and a
    projection borne by an adjacent wall and
    adapted to engage said slot, the conforma-
    tions of the projection and slot being such
    that, when the walls are extended, the plate
    will be interlocked with the projection when
    the plate is in one position, but will not
    be interlocked when in another position.
- 10   9. A cover for the purpose set forth com-
    prising a floor member that rises gradually
    from the edges toward the center so as to
    present a concave bottom and a convex top,
    and wall members connected to the floor
    member so that they may be extended below
    the floor member and retracted into the con-
    cavity of the floor member.
- 15   10. A cover for the purpose set forth that
    rises gradually from the edges toward the
    center so as to present a concave bottom and
    a convex top and embodies a marginal rein-
    forcing flange on its under side.
- 20   11. A cover for the purpose set forth hav-
    ing reinforcing webs on its under side and
    25 a plurality of walls pivoted thereto between
    said webs, so that they may be extended
    downwardly and retracted above the lower
    edge of the webs.
- 25   12. A cover of the character described
    bearing shiftable means adapted in one po-
    sition to engage the side of an excavation
    to limit lateral movement of the cover, and
    in another position to be ineffective in lim-
    iting such movement.
- 30   13. A cover of the character described
    bearing means pivoted thereto so that when
    said means is in one position it co-operates
    with the side of an excavation to limit lat-
    eral movement of the cover, and when in
    40 another position it is ineffective in limiting
    such movement.
- 35   14. A cover of the character described
    bearing retractile means on its bottom
    adapted to be extended from the bottom
    45 into a position wherein it co-operates with
    the side of an excavation to limit lateral
    shifting of the cover.
- 40   15. A cover of the character described
    having a recessed bottom and bearing means
    50 retractile into the said recess and adapted
    to be extended from its retracted position
    so as to co-operate with the side of an ex-
    cavation to limit lateral shifting of the
    cover.
- 55   55. In testimony whereof I hereunto affix my
    signature.

EDWIN H. STELZER.
